UNITED STATES PATENT OFFICE.

DAVID PUDLIN, OF NEW YORK, N. Y.

EYE FOR DOLLS.

1,330,718.

Specification of Letters Patent. Patented Feb. 10, 1920.

Application filed June 20, 1919. Serial No. 305,487.

To all whom it may concern:

Be it known that I, DAVID PUDLIN, a citizen of the United States, and a resident of the city of New York, borough of the Bronx, county of Bronx, and State of New York, have invented a new and Improved Eye for Dolls, of which the following is a full, clear, and exact description.

This invention relates to eyes for dolls and has for its main object to provide suitable means for connecting the eyes together in a novel, simple and inexpensive manner.

Another object of this invention is the provision of a rigid metallic bridge or connecting piece for the eyes provided with slotted ends whereby the eyes are adjustable relatively laterally on the bridge.

Another object is to provide an elastic or spring headpiece rotatably attached to the bridge piece to permit of the automatic adjustment of the eyes to the inequalities of the eye sockets.

Another object is to provide a convenient means for securely embedding the headpiece in the securing means for such headpiece.

Another object is to provide means for limiting the rotation of the eyes when in sleeping position.

Another object is to provide an eye carriage capable of being adapted to different widths of eye sockets and elastically held in position with such eye sockets.

The device proper comprises a rigid metallic bridge piece α provided with slotted ends in which the eyes are adjustably held by suitable securing means. The complete eye carriage constitutes a spring headpiece rotatably attached to the bridge and a counterweight rigidly secured to the bridge, the counterweight bar being provided with a stop for limiting the rotation of the eyes.

Referring to the drawing,

Figure 1 represents a vertical sectional view of a doll's head of usual construction showing my device in operative relationship therewith; and

Figs. 2, 3 and 4 represent respectively a front, rear and plan view of the device.

In the drawing I have shown a doll's head 1 of ordinary construction to which I have adapted my particular device. The device comprises a bridge piece α for carrying the eyes, such bridge piece being integrally constructed with a central bar 3 having two offset portions 4 and 5 and two

arms 6 and 7 bearing slots 8 and 9 in which the eyes 10 and 11 are secured by means of set screws 12 and 13. The eyes 10 and 11 are preferably hollow spherical bodies and are held in position on the bridge piece α so that the central bar 3 of the bridge piece α is in a line with their central diameter and forms their axis of rotation. The reason for this form of construction will be explained hereafter. The slots 8 and 9 in the bridge piece α permit of longitudinal adjustment of the eyes so that they may accommodate the various widths of eye sockets for heads of various sizes.

The bridge piece α is rotatably connected with a headpiece 14. This headpiece is constructed of resilient material and is adapted when secure in position to exert a spring pressure on the bridge piece α and hold the eyes under spring tension in their sockets. The headpiece 14 is provided with a large perforation 15 which acts to increase the elasticity of the metal of which the headpiece is constructed and at the same time affords a means whereby the cement used to secure the headpiece to the doll's head may penetrate and form a clamp over the edges of such perforation to more firmly secure the headpiece to the head.

The counterweight 16 is attached to a counterweight pendulum bar 17 which is rigidly secured to the bridge piece α and which is also provided with a stop 18 adapted to abut against the headpiece 14 when the eyes are in sleeping position and thereby limiting the rotation of such eyes.

It will be observed that the spring headpiece 14, being the bearing or journal for the bridge piece α , continually exerts a spring pressure on the central portion 3 thereof maintaining the axis of rotation of the spherical eyes 10 and 11 constant and consequently maintaining the eyes by virtue of their spherical contour in constant abutment in any position with the eye sockets of the head; in other words, the eyes being always under spring pressure automatically maintain their abutment with the eye sockets without any adjustment when once the bridge length is fixed.

Another important detail of this invention lies in the stop construction which is attached to the pendulum bar 17. The stop 18 is so arranged that when the eyes are in sleeping position practically all of the strain on the spring headpiece is removed

and the pendulum is so placed that the eyes are forced tightly against their sockets by the tendency of such pendulum to shift forward the axis of rotation of the eyes.

5. It is obvious that the details of construction of my device may be modified without departing from the general spirit of my invention.

What I claim and desire to secure by Letters Patent is:

1. The combination of a set of doll's eyes with a bridge piece and with resilient suspending means for automatically maintaining the said eyes in operative position, 15 counterpoise means operating in parallel with the eye axes, and means attached to the counterpoise means for relieving the tension on the resilient means when the eyes are in sleeping position.

20 2. The combination of a set of doll's eyes, with a bridge piece, said bridge piece being

provided with offset arms carrying longitudinal slots for adjustably holding the eyes and so arranged that the axis of rotation of the eyes and bridge piece shall coincide, resilient means carrying the bridge piece and adapted to automatically maintain the eyes therefor in their operative position. 25

3. The combination of a set of doll's eyes, with a bridge piece, said bridge piece being 30 provided with offset arms carrying longitudinal slots for adjustably holding the eyes and so arranged that the axis of rotation of the eyes and bridge piece shall coincide, resilient means carrying the bridge 35 piece and adapted to automatically maintain the eyes therefor in their operative position, said resilient means constituting a headpiece and being provided with a perforation to receive a fastening means to the head for holding the headpiece firmly in position. 40

DAVID PUDLIN.
